UNITED STATES PATENT OFFICE.

WILLIAM FAIRCHILD, OF ALBANY, NEW YORK.

CORE-SUPPORT AND BEARING MEMBER.

No. 865,775.

Specification of Letters Patent.

Patented Sept. 10, 1907.

Application filed April 27, 1907. Serial No. 370,704.

To all whom it may concern:

Be it known that I, WILLIAM FAIRCHILD, a citizen of the United States of America, and a resident of Albany, county of Albany, State of New York, have invented 5 a certain new and Improved Core-Support and Bearing Member, of which the following is a specification, reference being had to the accompanying drawings, forming a part thereof.

Core supports and bearing members of the type to 10 which this invention applies are employed in the making of castings containing holes for the reception of pintles and the like. A device of this character is filled with a core of loam or other mold material, and is then set in the mold with the pattern, being left in the mold 15 when the pattern is withdrawn. The metal is then poured into the mold, a portion of the metal flowing around the core support and bearing member and uniting solidly therewith. When the casting has cooled and is removed from the mold, the core of loam or other 20 molding material is removed, with the result that good clean bearings are formed in the casting. This obviates the expensive drilling that would otherwise be necessary; gives a clean hole, and further the metal of which the device is composed constitutes a lining which forms 25 better bearing material than would the cast metal itself.

The present invention comprises an improved form 30 of core support and bearing member which is simpler in construction and less expensive to manufacture than articles of a similar nature which have been constructed in the past. It is composed of but a single piece struck up with but a few operations from a blank.

In order that my invention may be fully understood, I will describe an embodiment thereof in detail, having 35 reference to the accompanying drawings illustrating same.

In the drawings Figure 1 shows a portion of a stove including a door and support therefor in which core supports and bearing members embodying my invention are employed. Fig. 2 is a view in detail of a blank from which the core support and bearing member is struck up. Fig. 3 is a view in side elevation of the core support and bearing member in process of construction. Figs. 4, 5 and 6 are respectively side, end, and perspective views of the same when completed and ready for use.

The present device is particularly adapted for use

in stove castings, and in Fig. 1 I have shown the same as so applied. In this figure reference character 11 designates a portion of a stove, and 12 a door hinged thereto. The support 11 has bearing lugs 13, and the door 12 has similar bearing lugs 14 arranged complementary thereto. Pintles 15 pass through openings in the lugs 14 and 13, whereby the parts are pivotally connected together; and each of the said lugs is provided with a 55 core support and bearing member 16 for receiving said pintles, such devices being illustrated in detail in the other figures. The device comprises a cylindrical shell 17, a back plate 18 and connecting elements 19, and is formed from the blank which appears in Fig. 2. 60 This blank comprises a central portion having lateral or side wings 20 and end portions 21, said end portions being connected with the main or body portion by means of narrow necks 22. The side wings 20 are curved over to form the central bearing portion 17, 65 while the end portions 21 are first bent at right angles to the central portion and then again at right angles, the portions 21 substantially meeting to form the back plate 18, while the narrow necks 22 form parts of the connecting elements 19.

From the foregoing, and from an inspection of the drawings, it will be apparent that a device so constructed is an extremely simple one and is very inexpensive to make. The device is used, as such devices are generally used, by filling the cylindrical portion 17 with 75 molding sand, and then inserting the device in the mold with the pattern. When the pattern is removed the device is left in place so that it finally becomes a part of the casting, as above explained.

What I claim is:

1. A core support and bearing member comprising a single integral structure having a cylindrical body portion and wings which are turned over at right angles thereto and then again at right angles to themselves, the latter portion substantially meeting and forming a rear plate, substantially as set forth.

2. A device of the character described comprising a single integral structure composed of a thin sheet of metal, the blank of which has lateral wings 20 and end portions 21 connected by narrow necks 22, said lateral wings 20 curved over to form a cylindrical member 17, the end portions 21 being folded over parallel with the cylindrical portion to form a back plate 18.

WILLIAM FAIRCHILD.
